LUGGAGE CASE

Julius Ritter, Jr. and Syevirous Essmus, Racine,
Wis., assignors to Hartmann Trunk Company,
Racine, Wis., a corporation of Wisconsin

Application March 16, 1936, Serial No. 69,053

2 Claims. (Cl. 190—41)

The present invention relates to improvements in luggage cases of the type equipped with adjustable fixtures for folding and confining one or more garments within the carrier or container.

Many types of fixtures for folding and confining garments within an ordinary luggage case, comprising relatively movable body and cover sections, have heretofore been proposed. Most 10 of these prior fixtures are so complicated in construction and mode of operation, as to make their use by the general public impractical. While some of the prior fixtures for thus loading and confining men's garments within a carrier case 15 are relatively satisfactory, many of the prior devices are unsatisfactory for the purpose of loading and retaining relatively delicate dresses and other women's garments which are susceptible of being easily stretched, distorted and undesirably wrinkled or crushed. These delicate garments, due to their length, must frequently be folded several times before they are sufficiently compacted to permit confinement thereof within a section of a luggage case; and the mechanism 20 for effecting such folding and subsequent confinement should avoid sharp creasing, stretching and rubbing of the fabric.

It is, therefore, a general object of the present invention to provide an improved garment supporting fixture which, besides being extremely simple, compact and durable in construction, can be readily manipulated to load and unload fragile and delicate ladies' wearing apparel without danger of injuring, disheveling, distorting or shifting 35 such garments.

There are many types of garment confining luggage carriers on the market wherein a folding frame cooperates with loading bars removably mounted in a case section, in suitable brackets 40 or supports, at the inner end of the frame. In all prior arrangements of this general character, the supports or brackets for the loading bars are disposed so that when the case is opened and the frame is in a lowered position for the first 45 loading and folding step, said brackets hold the loading bars in a stacked relationship either in the plane of the frame, or at right angles to the plane of the frame in the afore-mentioned position. Consequently, with either arrangement, 50 when there is a movement of the loaded frame from the original position to the confining position, through an arc of 180°, there is either an increase or decrease in the distance between the loading bars and the folding bar at the outer 55 end of the frame. Consequently, during the

movement of the frame with the garments thereon to the confining position, there must necessarily be a distortion, stretching, or shifting of the garments, which is objectionable with respect to fragile garments.

A specific object of the present invention is to overcome the afore-mentioned difficulty by providing a luggage case of the character described wherein the individual garment bars are so disposed relative to the frame that the distance 10 between the same and the bar at the outer end of the frame is precisely the same in either the raised or lowered position of the frame, with the result that garments carried by the frame and bars are not shifted, distorted, or stretched during the manipulation of the frame from one position to another.

A more specific object of the invention is to provide a luggage case wherein a garment bar is carried by a bracket by being disposed in a slot 20 extending along the locus of points equidistant from the limits of movement of the frame.

Another specific object of the invention is to provide, in a luggage case, simple bracket means 25 for removably and shiftably carrying the ends of garment bars, and arranged so that said garment bars may be easily released and engaged by flexing one of the bracket members.

Another object of the invention is to provide a luggage case having easily manipulated means 30 for foldably confining a number of full length garments within one section of the case, while maintaining the other section of the case free for the reception of other luggage.

Still another object of the invention is to provide a luggage case and garment supporting means associated therewith, which are of light weight, but rigid and durable in construction, and which permits the manufacture of the case 35 at a minimum cost.

These and other objects and advantages of the invention will be apparent from the following detailed description.

A clear conception of an embodiment of the features constituting the present invention and 45 of the mode of constructing and operating luggage cases built in accordance therewith, may be had by referring to the drawing accompanying and forming a part of this specification in which like reference characters designate the same or 50 similar parts in the various views:

Fig. 1 is a transverse sectional view through the open luggage case, showing the garment folding frame positioned over the body section of the case preparatory to loading and folding garments; 55

Fig. 2 is a similar transverse sectional view through the open case, showing the garment supporting frame moved through an angle of approximately 45° and the resulting movement of a hanger bar relative to its supporting brackets, to compensate for the relative frame and bar position during the manipulation of the frame and prior to reaching its ultimate position;

Fig. 3 is a similar transverse vertical sectional view through the open case only with the garment supporting frame in loaded position within the cover section of the case;

Fig. 4 is a horizontal sectional view through the open luggage case taken on the line 4—4 of Fig. 1; and

Fig. 5 is an enlarged, fragmentary, detail sectional view showing a mounting bracket for the garment bars and the relationship between the same and the garment folding frame.

While the invention has been shown and described herein as being applied by way of illustration to a relatively small and light luggage carrier for ladies' garments, it should be understood that some of the novel features are more generally applicable to other types and classes of luggage carriers, and it is not the intent to limit the invention by such specific disclosure.

The improved luggage case illustrated in the drawing comprises in general a body section 8 having a cover section 9 pivotally or hingedly connected thereto by means of hinges 10. The garment folding and confining mechanism, of the improved construction, is mounted entirely within the cover section 9, but the garment folding frame is adapted to be moved down to extend over the body section 8 as in Fig. 1, for loading purposes. The body section 8 may be provided with the usual carrying handle 11, and the cover section 9 may be swung into engagement with the body section and locked thereto by means of the usual latches 12. The cover section 9 is held in substantially upright position when the body section 8 is disposed horizontally and the cover section 9 is in open position, by means of foldably connected stays or retainers 13 of the usual type.

The improved garment folding and supporting fixture comprises generally a garment folding frame 14 permanently and swingably supported by means of pivots 15 upon the inner side walls of the cover section 9 near the main hinge 10, said frame having an integral transverse garment folding bar or rod 16 connecting the outer ends of the side members of the frame 14 and remote from the pivots 15.

Mounted upon opposite inner wall portions of the cover section 9, adjacent the hinged end thereof, are a number of separated yieldable or flexible brackets 17. Each bracket 17 has an offset ear portion by which it is attached, and the major portion of the bracket is free and yieldable and extends angularly outwardly in a direction substantially equi-distant between the planes of the cover and body sections of the case, when the case is fully opened, and this direction of extent of the bracket is therefore at substantially 45° from either limit of position of the garment folding frame 14. The extending portion of each bracket is furthermore formed with an elongated slot 18, entrance to which is afforded by means of an outwardly flared and grooved end portion 19 of the bracket. For removable mounting in the brackets 17 and for cooperation with the folding frame 14, one or more similar garment carrier bars 20 are pro-

vided. Each bar 20 is formed with reduced stub ends 21 to engage and move in the slots 18 of the brackets 17 and adapted to coact with the slots 18 in a manner to prevent rotation of the bars relative to the brackets 17 while permitting movement of the bars longitudinally of the slots.

The luggage case may furthermore be provided with a garment protecting and confining flap 22 made of fabric and one end of the flap is permanently attached to the interior of the inner end of cover section 9. The opposite end of the flap is freely movable and adjustably carries a catch 23 which is cooperable with a hook 24 permanently secured within the swinging end of the cover section. When the loaded frame is positioned within the cover section said flap may be stretched tautly thereover and is so secured by means of the elements 23 and 24, and thereby serves to confine the frame and garments and to protect the latter. The body section 8 of the case is provided with stop blocks 25 secured to the inner portions of the side walls thereof, as shown in Figs. 1, 2, 3 and 4, and said blocks serve to limit the forward and downward swinging motion of the frame 14.

When it is desired to load the improved luggage case with garments, the garment bars 20 are first removed and the individual garments are folded over said bars which are then inserted in the brackets 17 in stacked relationship and at an angle of substantially forty-five degrees, relative to either section of the case. The engagement of a bar is extremely simple and it is only necessary to insert a stub end 21 in a bracket slot 18, after which the other bracket is flexed outwardly laterally, and the other stub end of the bar is pushed into the slot of the other bracket, being guided thereto by the grooved, flared portion 19. When one or more bars 20, carrying garments, are thus disposed in the brackets 17, said bars will be disposed in the position of Figs. 1 and 5, and the garments folded over the carrier bars extend out over the bar end 16 of the frame 14, as shown in broken lines in Fig. 1. The frame 14 may now be swung upwardly away from the blocks 25, whereupon the rod 16 becomes effective to fold the garments midway between the bars 20 and the garment ends. During the swinging movement of the frame, as it approaches a forty-five degree position, as in Fig. 2, the distance between the carrier bars and the frame bar increases, and ordinarily a pull would be exerted on the garments. This, however, is overcome, by the mounting of the carrier bars in the slots 18, so that during this movement, the bars are free to move upwardly slightly in the slots to compensate for the increased distance and to overcome any pull or elongation which might occur. This action is shown in Fig. 2, and with the continued movement of the frame toward the position of Fig. 3, the carrier bars gradually drop down in the slots, as the tension or pull thereon decreases. In connection with this action, it should be observed that the pivot mountings 15 for the frame 14 are located adjacent the slots 18 and intermediate the ends of the same. Therefore, said slots form a locus of points equidistant from given portions of the frame when it is in either limited position of movement. Obviously, in all positions of the frame, there is no pull or strain imposed on the garments, and during movement of the frame, when a slight elongation or pull might occur, the movement of the bars in the slots counteracts such tendency.

After the position of Fig. 3 is reached, the protecting flap 22 is secured in position in the manner previously described and the case sections may be closed relative to each other, the 5 folded garments then being confined entirely in the cover section.

From the foregoing description it will be apparent that the invention provides simple, compact and readily manipulable means for permitting 10 one or more full length garments to be effectively packed within a container of small size. Also, the folding and confining mechanism is ideally adapted for women's garments of a fragile character and imposes no strain, pull, or distortion 15 thereon.

It should be understood that it is not desired to limit the invention to the exact details of construction herein shown and described, for 20 various modifications within the scope of the claims may occur to persons skilled in the art.

What is claimed as the invention is:

1. A luggage case, comprising a pair of hingedly connected sections, a garment supporting frame pivotally mounted in one of said sections and 25 swingable from one position to another position at substantially a right angle to the first position, brackets fixedly carried by said one section and located adjacent the pivot of the frame and having fixed slotted arms extending at all times

at an angle substantially bisecting the angle traversed by the frame in moving from one limit to the other, and a garment engaging bar mounted directly in said brackets and slideable lengthwise along the slots in the arms thereof and directly 5 therein during swinging movements of the frame when the bar and frame are cooperating in the folding and confining of garments engaging both of the same.

2. A luggage case, comprising a pair of hingedly connected sections, a garment supporting frame pivotally mounted in one of said sections and swingable from one position to another position at substantially a right angle to the first position, brackets fixedly carried by said one section 10 and located adjacent the pivot of the frame and each of said brackets having a fixed arm with a slot therein, said slot extending at all times at an angle of approximately forty-five degrees relative to the extreme frame positions, and a garment engaging bar mounted directly in said brackets and slideable lengthwise along the slots thereof and directly therein during swinging movements of the frame when the bar and frame are cooperating in the folding and confining of 20 garments engaging both of the same.
